United States Patent Office

Des. 207,466
Patented Apr. 18, 1967

207,466

INSULATED JUG

Howard W. Phillips, Nashville, Tenn., assignor to Aladdin Industries, Incorporated, Chicago, Ill., a corporation of Illinois

Filed Aug. 13, 1965, Ser. No. 86,576

Term of patent 14 years

(Cl. D58—17)

Fig. 1

Fig. 2

Fig. 3

FIG. 1 is a front elevational view of an insulated jug showing my new design,

FIG. 2 is a side elevational view thereof, and

FIG. 3 is a top view thereof.

I claim:

The ornamental design for an insulated jug, substantially as shown.
